METHOD OF AND APPARATUS FOR HANDLING HOT METAL BARS

Jerome R. George, Worcester, Mass., assignor to
 Morgan Construction Company, Worcester,
 Mass., a corporation of Massachusetts

Application May 18, 1928, Serial No. 278,732

24 Claims. (Cl. 80—42)

The present invention relates generally to the handling of hot metal bars as delivered from a rolling mill. More particularly, the invention resides in certain improvements upon existing methods of handling relatively thin flat rolled stock, for example, material known as "spring flats" as used in the manufacture of springs. As is well known, such material ordinarily requires annealing, and it is advantageous to secure this annealing, during cooling, by the "pack method", i. e., with the pieces assembled face to face in a pack or pile to so retard their cooling that the desired annealing is secured, after which the pieces are handled separately.

According to the present invention, this packing is secured in an improved manner, which necessitates for its accomplishment no interruption to the forward travel of the pieces as they are delivered from the mill; furthermore, once the pack has been formed to the desired thickness, provision is made for the uniform maintenance thereof and the subjection of each piece to the same annealing effect by procuring, at each addition of a fresh piece to the rear of the pack, the removal of the foremost piece at the front of the pack. The mechanism by which the annealed pieces are thus individually discharged from the pack is readily adjustable to stock of varying width and thickness, as are also the pack-forming and pack-maintaining instrumentalities. Furthermore, provision is made in connection with this discharge mechanism for depositing each individual piece, flatwise, on a cooling bed or other broadside conveying means, so that the individual annealed pieces can thereafter be operated upon in any way desired.

Other objects and advantages of my invention are fully set forth in the following detailed description thereof, reference being had in this connection to the accompanying drawings, wherein—

Figs. 1 and 1a (the latter a continuation of the former) illustrate diagrammatically, in plan view, the apparatus by which the successive pieces of stock, as delivered flatwise from the mill, are, in their continued forward movement, gradually warped or tipped into an inclined position as a preliminary to packing.

Figs. 2, 3, 4, 4a and 4b are transverse sectional views on an enlarged scale, the sections being taken, respectively, on the lines 2—2, 3—3, 4—4a—4a and 4b—4b of Figs. 1 and 1a.

Fig. 5 is a fragmentary large scale plan view of the pack-forming instrumentalities.

Fig. 6 is a view in side elevation of the pack-forming instrumentalities.

Fig. 7 is a transverse sectional view, illustrating the pack-receiving table or plate in its relation to the pack-maintaining and pack-discharging devices.

Fig. 7a is a fragmentary sectional view on the line 7a—7a of Fig. 7.

Figs. 8, 9, 10 and 11 are fragmentary views, partly diagrammatic, illustrating successive steps in the operation of removing or discharging the foremost piece from the pack.

Fig. 12 is a large scale fragmentary sectional view on the line 12—12 of Fig. 6.

Like reference characters refer to like parts in the different figures.

Referring first to Figs. 1 and 1a, I have indicated at 1, 1 a series of conveyor rollers constituting a part of the run-out table from a rolling mill whose final stand of reducing rolls is indicated at 2—it being understood that the rapidly moving hot metal product, cut into pieces of appropriate lengths by a shear, as indicated diagrammatically at 2a, is carried forward on these rollers 1, 1 and on other subsequent rollers 20 or conveying means toward the receiving devices that constitute its ultimate destination,—here being shown as the two cooling beds 3, 3. Inasmuch as these receiving devices are provided in duplicate, arrangement is made for selectively directing the stock, as carried forward on the conveyor rollers 1, 1, to either of said receiving devices; as here shown, a switch 4, operable by any suitable means such as a steam cylinder and piston unit 5, is adapted to be disposed, when desired, 30 either in its full or in its broken line position, Fig. 1, thereby to direct the stock for its continued forward movement either onto a set of conveyor rollers 6, 6 or onto a parallel set of conveyor rollers 6', 6'.

As shown clearly in Figs. 1, 1a, 2 and 3, suitable driving means, such as motors 7, 7 are provided for the set of rollers 1, 1 and for the sets of rollers 6, 6 and 6', 6', the arrangement preferably being such, in respect of the last-named sets of rollers, that each motor serves for two rollers, one in each set. In the flatwise forward movement of the stock, both on the rollers 1, 1 and on the rollers 6, 6 and 6', 6', said stock is preferably guided and also supported in 50 the spaces between adjacent rollers, by the relatively wide troughs 8 in the case of the rollers 1, and by the relatively narrow troughs 9 in the case of the rollers 6 and 6'.

The invention contemplates the packing or

55

stacking of the pieces in face-to-face contact, on a bed or table engaged by the edges of said pieces, and to facilitate this last, it is proposed, during the continued forward movement of each piece of stock, to warp or twist the latter gradually from its flatwise delivery position into the desired inclined position so that when delivered or projected onto the pack or stack, it will already have been turned, throughout its entire length, into substantially the requisite angle from the horizontal. For example, beyond the sets of conveyor rollers 6, 6 and 6', 6' are placed the several sets of motor-driven alined frusto-conical conveyor rollers 10, 10, 11, 11, 12, 12 and 10', 10', 11', 11' and 12', 12', these gradually increasing in the steepness or pitch of their stock conveying surfaces. As shown in Figs. 4, 4a and 4b, the guide troughs 13, 13a and 13b, associated respectively with these frusto-conical conveyor rollers, are correspondingly of steeper and steeper slope, with the result that each piece of forwardly moving stock is gradually warped more and more from a horizontal flatwise position as it travels on these rollers and through these troughs. Said stock thus emerges therefrom tipped edgewise at an angle of substantially 35°, and this relation is maintained in suitable guide channels 14, 14, best shown in Fig. 5, associated with the receiving guides 15, 15. These direct the stock to cooperating pairs of pinch rolls 16, 16, beyond which are the fixed delivery guides 15a, 15a. Said pinch rolls 16, 16 have their axes set at the inclinations necessary to maintain the slanted position of the pieces, and they serve to give said pieces, successively, the necessary forward impetus to project them clear through and beyond the hollow guide arms or troughs 17, 17 that are placed to receive the stock from the guides 15a. Each hollow arm or trough 17 is arranged for packing operation at the receiving end of an elongated inclined hot bed or packing table 18, best shown in Figs. 5, 6, 7 and 12, and the mechanism for forming a pack or stack of pieces on one of these tables 18, having its surface at substantially 35° from the horizontal, is as follows:—

Each arm or trough 17 is pivoted at its rear end on an axis inclined to the vertical, as shown at 19, 19, Figs. 5 and 6, the inclination being such that the arm or trough will swing in a plane substantially parallel to the supporting surface of inclined plate 18. Regardless of the angular adjustment of arm or trough 17, its rear end is always maintained in position to receive the stock from the pinch rolls 16, 16, because it is pivoted at said rear end; said angular adjustment, as will now be described, serves, during the formation of the pack, to gradually elevate the front or delivery end of the arm or trough 17, thereby to secure the edgewise projection of successive pieces onto the plate 18, one above the other.

As shown, each arm or trough 17 is pivotally connected by a link 20 to a bell crank lever 21, the latter being fulcrumed, as shown at 22, on an axis having substantially the same inclination as the axis 19 of the arm. A rod 23 connects the bell crank 21 to a rocker arm 24, whose shaft 25 is here shown as having a worm and worm gear 26 from a vertical shaft 27, the latter being equipped with a hand wheel 28 in convenient reach of the operator. For the commencement of the pack-forming operation on plate 18, the hand wheel 28 is so adjusted as to swing the arm or trough 17 about its pivot 19 in a downward direc-

tion, such that the delivery end of said arm or trough lies close to the lower longitudinal edge of plate 18; in this position, the first piece of stock projected through said arm or trough 17 by the pinch rolls 16, 16 runs out longitudinally, substantially on edge and substantially parallel to this lower edge of plate or bed 18. Along said lower edge, the apparatus provides the alined stop surfaces 29, 29, projecting above the supporting surface of bed or table 18 and in a plane substantially at right angles to said surface, and said first-delivered piece of stock comes to rest with its lower face bearing against said stop surfaces 29, 29. The latter, constituting simply a stationary abutment along the lower edge of the bed 18 or table 18, may be formed in any suitable or desired manner; as here shown, said stop surfaces are provided by the rearward extensions of a plurality of stationary members 30, 30 which are attached by bolts 59, 59 to the several stationary skids 62, 62 of cooling bed 3; as subsequent pieces of stock are similarly delivered, the hand wheel 28 is turned to gradually elevate the delivery end of arm or trough 17, so that each succeeding piece will overlie the preceding one, to form ultimately on the plate 18 a pack or stack of superposed pieces, as shown in section by the broken lines a, a', Fig. 7. It is to be understood, of course, that in practice a single upward adjustment of arm or trough 17 by hand wheel 28 may be of sufficient magnitude to take care of the laying, in pack formation, of more than one of the successively projected pieces of stock, since my invention is not in any way limited to the need for elevating the arm or trough 17 after each piece of stock so laid.

As best shown in Fig. 7, provision is made for insuring the orderly deposit on plate 18 of the pieces of stock that constitute the pack through the use of a series of overlying adjustable members 31, 31, that extend transversely of the length of the pack, at appropriate intervals. These members 31 have their under surfaces bevelled, as shown at 31a, Fig. 7a, and in opposed relation to the upper edges of the pieces of stock as the latter are projected, as above described, onto the plate 18, and thus said members 31 serve as guiding and confining means to effectually overcome the tendency of any of the successively delivered pieces to be deflected away from edgewise contact with the plate 18 or from face or surface contact with the preceding piece in the pack. The overlying members 31, 31 are also capable of adjustment within suitable limits, not only to accommodate themselves, by their spacing from the plate 18, to the packing of different widths of bars, but also to accommodate themselves, in connection with the bar-discharging devices hereinafter described, to bars of different thicknesses.

As shown in Fig. 7, each set of members 31, 31 is supported, in overhanging relation to the plate 18, from a pair of bell cranks 32 and 33, having a common pivotal center 34 that is provided by the fixed framework 35. The short arm 36 of bell crank 32 is pivotally connected to the member 31 at 37, but the rocking of member 31 about this pivotal center 37 is limited by a link connection 38 between said member 31 and the short arm 39 of bell crank 33. Said link 38 is pivoted at 40 to said short arm 39 and at its other end provides an elongated slot 41 through which passes a pin 42 on member 31.

The bell cranks 32 and 33 terminate in handles 43 and 44 respectively, by which they may be swung, to adjust the members 31, carried as above

described by the bell cranks 32 and 33, to the packing and handling of different widths and also different thicknesses of stock. Said handles carry clamping devices 32a and 33a respectively, whereby they may be secured in any desired position of adjustment, to a fixed plate 45. As shown in Fig. 7 for purposes of illustration merely, the handle 43 on the right-hand side has been swung outwardly through a larger arc than the left-hand handle 43, thereby retracting right-hand member 31 to leave a greater space between its free end and the aligned stop surfaces 29, 29 than exists at the left-hand side of Fig. 7; this difference in spacing represents approximately the difference in thickness between one of the right-hand packed bars *a* on the one hand, and one of the left-hand packed bars *a'* on the other hand. In practice, of course, this difference would not exist at one and the same time. Similarly, in Fig. 7, to show how the apparatus can take care of the illustrated difference in width between the bars *a* and *a'*, the right-hand handle 44 has been thrown nearer to the vertical than the left-hand handle 44, thereby, through link 38, to rock the right-hand members 31 about pivotal center 37 farther away from plate 18—and it will be understood that this method of mounting the overhanging members 31, 31 permits of such spacings from the table 18 and from the end-stops 29, 29, respectively, as to adapt the apparatus to the packing and handling of stock that varies greatly in width and in thickness.

The office of the thickness adjustment provided for the overhanging members 31, 31 is clearly shown in the diagrams of Figs. 8, 9, 10 and 11. In these figures, the extreme end of member 31 overhangs the upper edge of the next lowest bar in the pack, but does not reach to the lowest bar, which latter must be left free for withdrawal in the manner now to be described. Said lowest bar, as shown, rests with its outer face against the row of end-stops 29, 29 and it is supported edgewise by the row of ledges 30a, 30a which are provided at the lower edge of plate 18 by the said members 30, 30. After the pack has been built up to the desired thickness or height, the arrival of each fresh piece of stock thereon must be accompanied by the delivery, from the pack, of its lowermost piece, in order that uniformity in the pack-annealing process shall prevail. To accomplish such delivery, a plurality of slides 46, 46, suitably spaced between the stationary end-stops 29, 29, are provided, these slides being operable in unison through their connection, by straps on the eccentrics 47, 47, to a driving shaft 48. The slides 46 at their outer ends are supported on rollers 49, the contact of said rollers being with suitably shaped cam surfaces 50, 50 formed on said slides.

In their normal retracted or rest position, said slides 46, 46 present an aligned row of notches 51, 51 in staggered relation to and underlying the supporting ledges 30a, 30a of the end-stops 29. With the delivery of each new piece to the completed pack, the shaft 48 is given one complete revolution, being connected for this purpose to any suitable driving mechanism, not shown. Such single revolution of shaft 48, through eccentrics 47, imparts an outward and a return movement to all the slides 46 in unison, and, due to the shape of each cam surface 50, bearing against supporting roller 49, the path of movement of each notch 51 is substantially that indicated by the arrows on Fig. 8.

At the commencement of this motion, the aligned notches 51, 51 move up from their rest position of Fig. 8 and engage that edge of the lowermost piece which rests on the ledges 30a of end-stops 29, so as to lift said lowermost piece off of said ledges 30a and to slide its face along the end-stops 29, as indicated in Figs. 9 and 10. This action takes place without interference from the overhanging members 31, 31, since the ends of the latter, as previously stated, are adjusted to terminate just short of the foremost piece of the pack. As shown in Fig. 10, the foremost piece has been moved far enough to clear the effective surface of the end-stops 29, and from this position said piece must continue to be moved upwardly until its lower edge, sustained on the row of notches 51, 51, is carried over the raised tips 52, 52 of the stationary members 30, 30. As shown in Fig. 10, the piece at this stage of its removal can either maintain its parallelism with the superposed pieces of the pack, or it can tip, having cleared the effective surface of end-stops 29, 29, into surface contact with the portions 53 of members 46 that lie beyond the notches 51. In any event, as the notches 51, 51 move further upwardly, along the path depicted by the arrows in Fig. 8, said piece undergoing removal ultimately finds its entire support on the slides 46, 46, with its lower edge in the notches 51, 51 and with its surface against the portions 53, 53 of said slides 46, 46. In this position, said piece undergoing removal, as shown in Fig. 11, is carried clear of the raised tips 52, 52 of the stationary cooling bed extensions 30, 30 and is finally deposited on the top surface of the cooling bed 3 as the slides 46, 46 embark upon the return portion of their path of movement, indicated by the arrows in Fig. 8. These raised tips 52, 52 effectually prevent any retrograde movement of the piece of stock so deposited on the stationary cooling bed members 62, 62.

It will be understood that each piece of stock so deposited on the cooling bed 3 thereafter comes under the influence of any suitable broadside transfer devices, associated with said cooling bed, 45 which devices are operated, in a manner well known in the art, to procure the movement of each individual piece across said bed, thereby making room for the deposit, as shown in Fig. 11, of the next succeeding piece of stock to be withdrawn, as above described, from the forward part of the pack on table 18. Such broadside transfer mechanisms for the individual movement of the pieces on the cooling bed 3 form no part of the present invention and hence no description thereof is necessary.

It is further to be noted that the pack-supporting surface of each elongated pack-receiving table 18, as shown in Fig. 12, is preferably formed in a plurality of sections 54, 54 that provide transverse spaced ridges 55, 55 for contact with the edges of the pieces of stock, and between these ridges the elongated depressions 56, 56. In this way, air is permitted to circulate upwardly in a plurality of currents across the face of the table 18, each current passing under the edges of the pieces of stock where said edges overlie the depressions 56, 56; this prolongs the life of the table 18 and prevents its surface from being warped by the excessive heat conducted and radiated from the packed material. By thus introducing currents of air beneath the lower edges of the packed pieces of stock, said lower edges are cooled at substantially the same rate as the upper edges of said packed pieces, thereby pre-

venting the cambering of the stock that might result from unequal cooling along its edges.

Also, as best disclosed in Fig. 6, the contact ridges 55 of the table 18 are preferably arranged diagonally, so that each piece of stock in the pack, as it gradually moves forward, owing to successive withdrawals of the pieces arriving against the stop surfaces 29, 29 as above described, has constantly changing points of contact with the table 18, and thus any hardening in spots, due to prolonged contact with the table of one or more points or spots, is effectually prevented. Furthermore, as shown in Fig. 12, the spaces or expansion joints between the table sections 54, 54 are preferably bridged by plates 57, to prevent undue impingement of cold air on the portions of the packed stock immediately overlying said spaces.

The operation of my improved apparatus, as above described, is such that full advantage is taken of the force of gravity in the maintenance of straight sides or edges in the pieces of stock being handled,—the latter, for the entire duration of the annealing process, being supported edgewise on the table 18. Not only that, but due to the inclination of said table, gravity acts to move the pieces step-by-step downwardly on said table, as each successive lowermost piece is removed from the bottom of the pack, and gravity also acts to keep the packed pieces close enough together, sidewise, to prevent any oxidation on their flat surfaces,—oxidation being limited to the edges. Once a pack has been formed, it is maintained at the desired thickness on table 18 by withdrawing a piece from the front as each fresh piece is added to the rear, and this, of course, involves the projection of all succeeding or following pieces onto the upper part of said table at about the same level, thus subjecting the surface of said table, at said level, to considerable wear. It is therefore desirable as shown in Fig. 7, to make the upper portion of table 18 in the form of a detachable and replaceable chilled iron member 58, adapted to better resist said wear and also to permit renewal whenever desired.

Provision is also made, as shown in Fig. 8, for lining up the row of supporting ledges 30a, 30a provided by the members 30, 30 that bridge the gap between the lower edge of table 18 and the stationary skids 62, 62 of the cooling bed. As shown, each connecting member or extension 30 is bolted at 59 to the adjoining member 62, and the two parts thus connected are adjustable horizontally in unison by means of a pair of adjusting screws 60, 60 carried by the stationary framework and bearing on opposite sides of an extension 61 depending from said connected members. Inasmuch as the opposing ends of table 18 and skids 30 are supported so as to be freely movable within certain limits, this adjustment allows all the stop surfaces 29, 29 to be brought into alignment.

These stop surfaces 29, 29 contact with the bottom piece of stock in the pack for slightly more than half of its width, as shown in Fig. 11, and from that point on each surface is cut back toward the raised tip 52 in order to reduce as much as possible the length of the substantially elliptical path of the movable notches 51, 51, which path is shown by the arrows in Fig. 8; this construction allows prompt separation of the lowermost piece of stock from the pieces immediately above it.

I claim:

1. In the art of handling hot metal bars, as delivered flatwise longitudinally from a rolling mill, the improvement which consists in continuing the forward longitudinal delivery movement of said bars to project them longitudinally onto an inclined supporting surface, and procuring by the movement of each bar toward said surface the progressive warping of same into a plane substantially at right angles to said surface. 10

2. In the handling of hot metal bars, as delivered longitudinally, flatwise, from a rolling mill, the improvement which consists in gradually warping each bar, by continuance of its forward movement, into a position of partial 15 edgewise support, and projecting it in that condition onto an inclined supporting surface.

3. In the handling of hot metal bars, as delivered longitudinally, flatwise, from a rolling mill, the improvement which consists in gradually warping said bars, by continuance of their forward movement, from a condition of flatwise support into a condition of partial edgewise support, and projecting said bars longitudinally edgewise onto an inclined supporting surface, in 25 face-to-face contact.

4. In the handling of hot metal bars, supported flatwise and delivered successively, longitudinally, from a rolling mill, the improvement which consists in procuring, by the continued 30 forward movement of each bar, its gradual lateral warping to a condition of partial edgewise support, and projecting edgewise the successive bars so supported onto an inclined supporting surface one against the other in pack 35 formation, with the foremost bar of said pack in surface contact with a plurality of fixed stops.

5. In apparatus of the class described, conveying means for the longitudinal movement, flatwise, of successively delivered bars, a support 40 whereon to receive said bars edgewise, in pack formation, and interposed means for procuring by the continued longitudinal movement of said bars, their warping into a condition of partial edgewise support. 45

6. In apparatus of the class described, conveying means for the longitudinal movement, flatwise, of successively delivered bars, means for procuring, by the continued longitudinal movement of said bars, their warping into a condition of partial 50 edgewise support, an inclined table for the reception of said bars in pack formation, and means for projecting the so-warped bars longitudinally edgewise onto said table.

7. In apparatus of the class described, an inclined support whereon to receive bars in pack formation, resting edgewise on said support, means for projecting successively delivered bars longitudinally onto said support, and means for elevating the delivery end of said projecting 60 means to procure the deposit of each bar against the one preceding. 55

8. In the assemblage of successively delivered metal bars in pack formation, the improvement which consists in projecting successive bars longitudinally onto a support, in edgewise contact therewith, and shifting periodically the line of projection of said bars to procure their face-to-face contact with each other. 65

9. In the assemblage of successively delivered metal bars in pack formation, the improvement which consists in projecting successive bars longitudinally onto an inclined supporting surface, in edgewise contact therewith, and elevating the 70 75

- line of projection of succeeding bars over those preceding, in order to build them up, one against the other, on said support.
10. In apparatus of the class described, a support whereon to assemble successively delivered bars in pack formation, means for longitudinally projecting said bars onto said support, in edge-wise contact therewith, and adjustable means on the delivery side of said projecting means to shift the line of projection of said bars.
11. In apparatus of the class described, a support whereon to assemble successively delivered bars in pack formation, means for longitudinally projecting said bars onto said support, and a 15 guide device for said bars on the delivery side of said projecting means with the entrance end of said guide device in the line of projection from said projecting means, and with the other end of said guide device shiftable, to direct said bars to different locations on said support.
12. In apparatus of the class described, a support whereon to assemble successively delivered bars in pack formation, means for longitudinally projecting said bars onto said support, in edge-wise contact therewith, and a guide arm with its entrance end in the line of projection from said projecting means, said guide arm being pivoted at said entrance end, to permit the sweep of its other end across the width of said support.
13. In apparatus of the class described, a table for the support, on edge, of bars in pack formation, means for delivering bars longitudinally to said table, and means overlying said table to guide and control the movements of said bars in the process of forming said pack.
14. In apparatus of the class described, a table for the support, on edge, of bars in pack formation, means for delivering bars longitudinally to said table, and means overlying said table to guide and control the movements of said bars in the process of forming said pack, said means being adjustable to conform to the width of the bars being packed.
15. In apparatus of the class described, a table for the support, on edge, of bars in pack formation, means for removing successively, each foremost bar of said pack, and means for preventing displacement of other bars in said pack during the operation of said removing means on the foremost bar.
16. In apparatus of the class described, a table for the support, on edge, of bars in pack formation, means operable on the foremost bar of said pack to remove the same, and devices engaged with the upper edges of other bars in said pack to prevent their displacement when the foremost bar is removed, said devices being adjustable to conform to the thickness of the bar stock.
17. In apparatus of the class described, a table for the support, on edge, of bars in pack formation, means operable on the foremost bar of said pack to remove the same, and devices engaged with the upper edges of other bars in said pack to prevent their displacement when the foremost bar is removed, said devices being adjustable to conform to the thickness of the bar stock, and means for fixing said devices in a position of adjustment that permits removal only of the foremost bar.
18. In apparatus of the class described, an in-

clined table for the support, on edge, of bars in pack formation, means for delivering bars longitudinally to said table, and means overlying said table to guide and control the movements of said bars in the process of adding bars to and discharging bars from said pack, said means being adjustable to conform to the thickness of an individual bar.

19. In apparatus of the class described, an inclined table for the support, on edge, of bars in pack formation, means for delivering bars longitudinally to said table, and means overlying said table to guide and control the movements of said bars in the process of adding bars to and discharging bars from said pack, said means being adjustable to conform to the width of an individual bar.

20. In apparatus of the class described, an inclined table for the support, on edge, of bars in pack formation, means for delivering bars longitudinally to said table, and means overlying said table to guide and control the movements of said bars in the process of adding bars to and discharging bars from said pack, said means being adjustable to conform to the width and thickness of an individual bar.

21. In apparatus of the class described, a table for the support, on edge, of bars in pack formation, means operable on the foremost bar of said pack to remove the same, and devices engaged with the upper edges of other bars in said pack to prevent their displacement when the foremost bar is removed, said devices being adjustable to conform to the thickness and width of the bar stock, and means for fixing said devices in a position of adjustment that permits removal only of the foremost bar.

22. In apparatus of the class described, an inclined table for the support, on edge, of bars in pack formation, means operable to remove bars successively from the front of said pack, whereby each bar moves step-by-step across said table, the latter having spaced transverse contact ridges whereon rest the edges of said bars, with said ridges extending diagonally, whereby movement of each bar brings a fresh edge surface into contact with said ridges, thus to prevent prolonged contact of any one spot on each bar with said table.

23. In apparatus of the class described, an inclined table, means for delivering successive bars to said table in edge-wise contact therewith, said bars accumulating side by side thereon to form a pack, and means for withdrawing a bar from the front of said pack for each bar thereafter added to the rear of said pack, the surface of said table being renewable in the zone where bars are added to the rear of said pack.

24. In apparatus of the class described, an inclined table for the support on edge of bars in pack formation, a cooling bed adjacent to the lower edge of said table, means operable on successive foremost bars of said pack to deposit them on the stationary skids of said cooling bed, and adjustable means carried by the ends of said stationary skids, for surface contact with the foremost bar of said pack, to resist the gravitational descent of said pack on said table.
